DESIGN FOR A KNIFE AND SHEARS DESK SET SUPPORT

Rolland F. McCrillis, Norwalk, Ohio

Application December 2, 1939, Serial No. 88,637

Term of patent 7 years

To all whom it may concern:

Be it known that I, Rolland F. McCrillis, a citizen of the United States, residing at Norwalk, in the county of Huron and State of Ohio, have invented a new, original, and ornamental Design for a Knife and Shears Desk Set Support, of which the following is a specification, reference being had to the accompanying drawing, forming part thereof.

In the drawing, Fig. 1 is a plan view of a knife and shears desk set support embodying the new design.

Figs. 2 and 3 are front and rear elevations, respectively, of the support.

Figs. 4 and 5 are right end and left end elevations, respectively, of the support.

Fig. 6 is a section on the line 6—6 of Fig. 2.

I claim:

The ornamental design for a knife and shears desk set support, as shown.

ROLLAND F. McCRILLIS.
